UNITED STATES PATENT OFFICE.

HANS SIEGWART, OF LUZERN, SWITZERLAND.

TUBULAR BODY SUCH AS A PIPE, HOLLOW MAST, OR THE LIKE.

1,076,611.

Specification of Letters Patent.

Patented Oct. 21, 1913.

Original application filed November 5, 1910, Serial No. 590,780. Divided and this application filed September 20, 1911. Serial No. 650,455.

To all whom it may concern:

Be it known that I, HANS SIEGWART, a citizen of the Swiss Confederation, residing at Lucerne, Switzerland, have invented certain new and useful Improvements in Tubular Bodies such as Pipes, Hollow Masts, or the like, of which the following is a specification, this application being divisional of my application Serial No. 590,780, filed November 5, 1910.

This invention is for improvements in or relating to tubular bodies such as pipes, hollow masts or the like from lengths or fillets of artificial stone or similar material.

According to this invention the lengths or fillets of artificial stone are built upon a core and secured together by some adhesive material such as cement that can be introduced between the fillets while soft and afterward hardens and holds the parts together. The fillets with the cementing medium are held in place upon the core by a binding or wrapping sheet of sacking or other suitable material.

In manufacture the fillets are mounted upon the sacking or other binding, the fillets being arranged end to end longitudinally upon the binding and spaced apart a convenient distance. The cementing medium is then applied between the fillets and the band or binding of sacking and thus loaded (conveniently while in a flat state) is wrapped around the core and holds all the parts in place until the cementing medium has set.

In the accompanying drawings, which illustrate by way of example one embodiment of this invention, Figure 1 shows a cylindrical tube in transverse section, Fig. 2 shows two of the fillets on the binding material, and Fig. 3 shows the arrangement of the fillets on the binding material.

Like letters indicate like parts throughout the drawings.

The fillets 1 which are small brick-like members of convenient length are laid side by side and end to end in rows upon a flexible wrapping sheet or band of binding material 2, the width of which is equal to the circumference of the tubular body to be formed. The fillets are spaced apart a convenient distance as shown and form a layer in which those in one row break joints with those in the next. Longitudinal reinforcing rods, say of iron, 3 are dropped in between the rows and then a suitable binder such as

cement which can be applied soft and will afterward harden is introduced between the fillets. During these operations, the flexible sheet or band is conveniently retained in a flat state (Figs. 2 and 3), but when loaded, as described, it is wrapped around the core with the rods and rows of fillets extending longitudinally and thus all the parts are brought into the position shown in Fig. 1. When the cementing medium has set the tubular body thus formed can be removed from the core and a lining 4 of cement or asphalt may be applied to the interior. The exterior may be similarly coated if desired, either after or before removal from the core. In some cases it is preferred to apply a winding of reinforcing wire 5 to the exterior of the tubular body before it is removed from the core and then to cover this with a coating of cement, asphalt or other material 6. It will be seen that the same result may be attained by building up the fillets around the core and filling in between them with the cementing medium as the construction proceeds, the whole being afterward bound together with sacking or other material and left to harden.

What I claim as my invention and desire to secure by Letters Patent is:—

1. A tubular body comprising fillets shorter than the tubular body and arranged in spaced relation end to end in rows longitudinally of the tubular body with their inner corners in adjacent rows substantially in contact and their outer corners angularly spaced, an adherent binder in the spaces between the fillets, reinforcing rods extending longitudinally in the angular spaces between the rows of fillets, and a flexible wrapping sheet surrounding and holding the layer of fillets and the rods.

2. A tubular body comprising fillets shorter than the tubular body arranged side by side with angular spaces between all adjacent parts of the fillets and end to end in spaced relation with spaces between all parts of the adjacent ends of the fillets to form a tubular layer of spaced fillets in which the fillets are completely separated from one another longitudinally of the tubular body and are angularly spaced circumferentially thereof, an adherent binder in all the spaces between the fillets, a flexible wrapping sheet surrounding and holding the layer of fillets and the binder, a reinforcing winding out-

side of the wrapping sheet, and a plastic layer covering the winding.

3. A tubular body comprising fillets having six plane sides, such fillets being shorter than the tubular body and arranged side by side with angular spaces between adjacent plane sides of the fillets and end to end in spaced relation with spaces between all parts of adjacent plane end surfaces to form a tubular layer of spaced fillets in which the fillets are completely separated from one another longitudinally of the tubular body and are angularly spaced circumferentially thereof, an adherent binder in all the spaces between the fillets, a woven fabric wrapping sheet surrounding and holding the layer of fillets and the binder, and a wire reinforcing winding proximate to the outside of the woven fabric wrapping sheet.

4. A tubular body comprising fillets shorter than the tubular body and arranged in spaced relation end to end in rows longitudinally of the tubular body with their inner corners in adjacent rows substantially in contact and their outer corners angularly spaced, an adherent binder in the spaces between the fillets, and reinforcing rods extending longitudinally in the angular spaces between the rows of fillets.

5. A tubular body comprising fillets shorter than the tubular body and arranged in spaced relation end to end in rows longitudinally of the tubular body with their inner corners in adjacent rows substantially

in contact and their outer corners angularly spaced, an adherent binder in the spaces between the fillets, reinforcing rods extending longitudinally in the angular spaces between the rows of fillets, a flexible wrapping sheet surrounding and holding the layer of fillets and the rods, and a wire reinforcing winding proximate to the outside of the wrapping sheet.

6. A tubular body comprising oblong fillets shorter than the tubular body arranged in spaced relation end to end in rows longitudinally of the tubular body with their inner corners in adjacent rows substantially in contact and their outer corners angularly spaced and with the fillets in any one row breaking joints with those in the next adjacent rows, an adherent binder in the spaces between the fillets, strengthening rods extending longitudinally in the angular spaces between the rows of fillets, a flexible wrapping sheet surrounding and holding the layer of fillets and the rods, an inextensible reinforcing winding proximate to the outside of the wrapping sheet, a plastic layer outward from the wrapping sheet, and a plastic layer inward from the layer of fillets.

In testimony whereof I have signed my name to this specification in the presence of two subscribing witnesses.

HANS SIEGWART.
